UNITED STATES PATENT OFFICE

JOSEPH WUYTS, OF STATEN ISLAND, NEW YORK, ASSIGNOR TO BLACK, STARR AND FROST, OF NEW YORK, N. Y.

DESIGN FOR A PLATE OR SIMILAR ARTICLE

Application filed September 22, 1930. Serial No. 37,034. Term of patent 3½ years.

To all whom it may concern:

Be it known that I, JOSEPH WUYTS, a subject of the Kingdom of Belgium, residing at Staten Island, in the county of Richmond and State of New York, have invented a new, original, and ornamental Design for a plate or Similar Article, of which the following is a specification, reference being had to the accompanying drawing, forming part thereof.

The figure is a plan view of a plate showing my new design.

I claim:

The ornamental design for a plate or similar article, as shown.

J. WUYTS.
